UNITED STATES PATENT OFFICE

2,134,574

ELECTRIC INCANDESCENT LAMP

Emma B. Pinkle, East Cleveland, Ohio, assignor
to General Electric Company, a corporation of
New York

Application August 24, 1937, Serial No. 160,621

3 Claims. (Cl. 176—38)

My invention relates to electric incandescent lamps and more particularly to high wattage lamps. Still more particularly, my invention relates to an improved joint between the lamp filament and its leading-in conductors.

Heretofore, in high wattage lamps of the type wherein the filament comprises a number of coiled segments arranged substantially parallel to each other, it has been the practice to wind the filament with extra coiled segments at the ends thereof which were short-circuited by inserting a mandrel therein and then welded together with their mandrels to the leading-in conductors. Such a joint has the disadvantage that the mandrel may not make a positive contact with some of the turns of the end segment so that those turns are heated by the current passing through the lamp thereby increasing the effective length of the filament over its designed length. Moreover, the welding operation tends to make the tungsten filament brittle so that it is liable to break off if the lamp is jarred.

One of the objects of my invention is to provide an improved form of joint between the filament and the leading-in conductors. Another object is to provide a joint in which the end segments of the filament are effectively short-circuited. Still another object is to greatly increase the strength of the joint and to provide a good mechanical and electrical connection of the filament to the leading-in conductors.

Further objects and advantages of my invention will appear from the following description of a species thereof and from the drawing in which Fig. 1 is an elevation of one form of incandescent lamp embodying my invention; Fig. 2 is an elevation, partly in section and on an enlarged scale, of a portion of the filament joint; and Fig. 3 is a section along the line 3—3 of Fig. 1 showing a portion of the filament and its supporting structure.

Referring to the drawing, the lamp shown therein comprises a glass bulb 10 having a base construction of the type shown and claimed in United States Patents Nos. 1,967,852 and 2,069,638, D. K. Wright, and consisting of a pressed glass cup portion 11 having tubular bosses 12—12 thereon to which are sealed metal thimbles 13—13 which serve for mounting the lamp and for conducting current thereto. Channel-shaped metal supports or leading-in conductors 14—14 are secured at their ends within the thimbles 13—13 and extend into the bulb 10. The leads 14—14 may be made of nickel-plated steel and 55 may be provided with rod or wire end portions

15—15, of molybdenum for example, welded thereto and extending on opposite sides of the tungsten filament 16. The leads are held in rigid spaced relationship by cross-bars 17—18 of insulating material, preferably a ceramic material such as 5 siliminite. The cross-bar 17 is secured to the leads 14—14 by short lengths of wire 19—19 threaded through holes in the ends of the cross-bar and in the leads and welded to the leads. The cross-bar 18 is secured to the ends of the 10 lead extensions 15—15 by similar wires 20—20 welded to said extensions.

The filament 16 illustrated in the drawing is of the biplane type comprising a plurality of parallel coiled segments joined by upper and 15 lower uncoiled or bight portions 21 and 22 respectively, the alternate segments in this case being located in separate planes so that one-half of said segments are in one plane and the other half of said segments are disposed behind said 20 first half in another plane. The filament is supported at the top by support wires 23 having hooked lower ends engaging the upper bights 21 and secured at their upper ends to the cross-bar 17. The lower bights 22 are rigidly secured, 25 preferably by welding, to the upper ends of anchor wires 24, the lower ends of which are rigidly secured to an insulating bridge member 25 which may be made of zircon. The said anchors may be embedded in the bridge 25. Each of guide 30 wires 26—26 has one end secured to the bridge 25 and the other end loosely coiled around a lead extension 15 so as to be freely slid able thereon so that the filament 16 is free to expand in a longitudinal direction and the bridge 25 moves 35 therewith but is prevented from rotating by the said guide wires 26 thereby preventing the segments of the filament from twisting. The bridge 25 is further guided by a wire 27 secured thereto and extending through a hole in the cross-bar 18. 40

Each end of the filament 16 is wound with a coiled segment 28 (Fig. 2) over which is screwed a coil 29, preferably of tungsten wire, of substantially the same length as the said segment 28 to short-circuit the said segment. The coil 29 is 45 of the same pitch as the segment 28 and preferably is made of a wire of slightly smaller diameter. A conductive support or mandrel 30 extends through the segment 28 which is securely held between a hooked end 31 of the mandrel 50 and the cross-bar 17, the said mandrel extending through a hole in said cross-bar and being secured, preferably by welding, to the lead 14. The hook 31 on the end of mandrel 30 may be omitted if desired since the segment 28 grips the mandrel 55

quite tightly. Such a joint adds greatly to the strength of the lamp, provides a good mechanical and electrical connection of the filament to the leads and assures the short-circuiting of all of the turns in the filament end segments 28.

What I claim as new and desire to secure by Letters Patent of the United States is:

1. In an incandescent lamp, the combination of a conductive lead, a filament having a coiled end portion, a coil screwed over said coiled end portion of said filament and short-circuiting the turns thereof, and a conductive mandrel in contact with and extending through said coiled end portion of said filament and secured to said conductive lead at a point removed from said coils.
2. In an incandescent lamp, the combination of a pair of spaced conductive leads, an insulating cross-bar extending between said leads, a filament

having a coiled end portion, a coil screwed over said coiled end portion of said filament and short-circuiting the turns thereof, and a conductive mandrel in contact with and extending through said coiled end portion of said filament and through said cross-bar to one of said leads, said filament end portion and the coil thereon being securely held between said cross-bar and the end of said mandrel.

3. In an incandescent lamp, the combination of a filament, a conductive support for supplying current to said filament, said filament having a coiled end portion surrounding and making electrical contact with said support, and a coil screwed over said coiled end portion of said filament and short-circuiting the turns thereof.

EMMA B. PINKLE.
